Primary Examiner — Rhea Shields

(57) CLAIM

The ornamental design for a mascara brush, as shown and described.

DESCRIPTION

1.1 is a front view;

1.2 is a top view;

1.3 is a side perspective view;

1.4 is a side view; and

1.5 is a bottom view.

In the drawings, the broken lines are for the purpose of illustrating portions of the mascara brush that forms no part of the claimed design.
